WINDING MECHANISM

Original Filed Aug. 23, 1927

UNITED STATES PATENT OFFICE

AUGUSTUS F. KLASING, OF CHICAGO, ILLINOIS

WINDING MECHANISM

Original application filed August 23, 1927, Serial No. 214,916. Divided and this application filed September 1, 1928, Serial No. 303,535. Renewed January 20, 1930.

My invention relates to railway car hand brakes and has particular reference to winding means embodied in the same.

An important object of the invention is to provide means whereby a chain may be wound upon a drum in a manner whereby the wound chain will have the minimum diameter whereby the maximum leverage is obtainable.

The present application is a division of my co-pending application for railway car hand brakes, filed August 23, 1927, Serial No. 214,916.

In the accompanying drawings, forming a part of this specification, and in which like numerals are employed to designate like parts throughout the same:

Figure 1 is a side elevation of a winding device embodying my invention,

Figure 2 is a front face elevation of the same,

Figure 3 is a central vertical longitudinal section through the same,

Figure 4 is a vertical section taken on line 4—4 of Figure 1,

Figure 5 is an enlarged fragmentary side elevation of the winding drum, and,

Figure 6 is a partly diagrammatic section, extending longitudinally through the winding drum, illustrating the manner in which the chain is wound upon the same.

The upper unit of the brake mechanism embodies a housing 20, closed at the top and opened at the bottom, and this housing is carried by an inner vertical plate 21, preferably formed integral therewith. This plate is provided with apertured lugs 22, at its top, and apertured extensions 23, at its bottom, for receiving bolts 24, or the like, to attach the housing to the car body. This housing is preferably located upon the end of the car body adjacent to the top thereof. The housing provides a cantilever bracket, and the housing is suitably reinforced with ribs, to prevent distortion of its shape, when subjected to undue strains.

The housing 20 is provided in its top with a vertical sleeve-bearing 26, rotatably receiving a vertical shaft or staff 27, extending above the same. Formed integral with the lower end of the shaft 27 is a bevel-pinion 28,

operating within the housing 20. By forming the bevel-pinion integral with the lower end of the shaft, its necessary pitch diameter is reduced, thereby requiring a co-acting gear wheel, to be described, of smaller diameter than ordinarily employed. However, the gear wheel of smaller diameter than ordinarily employed provides ample leverage for developing the required power. The combination of the bevel-pinion integral with the shaft, and the corresponding relative small diameter of the bevel gear wheel, renders it possible to construct a brake mechanism of small size and proportion and which is more suitably applicable for attachment to the ends of cars of different constructions, and furthermore, providing a brake mechanism of light weight. The upward displacement of the vertical shaft 27 is prevented by the bevel-pinion 28, while its downward displacement is prevented by a washer 29, surrounding the shaft 27 and engaging the top of the sleeve-bearing 26. This washer is provided with a groove formed by a pair of spaced upstanding lugs 30, receiving therein a cotter-pin 31, passing through an opening in the vertical shaft 27. The washer 29 rotates with the vertical shaft, thus preventing shearing action of the cotter-pin. At its upper end, the vertical shaft 27 is equipped with the usual horizontal hand wheel (not shown) to rotate the same. Other means may be employed to turn the vertical shaft, such as a lever, or the like.

Arranged within the housing 20 is a horizontal shaft 32', the inner end of which is journaled in a bearing 33, formed in the vertical plate 21, and the outer end of which is journaled in a bearing 34, formed in the outer side of the housing. The shaft 32' is held stationary by means of a cotter-pin 35, passing through an opening 36 in the outer end of the shaft 32' and through openings in lugs 37, formed integral with the housing, as shown.

Rotatable upon the horizontal shaft 32' is a gear wheel 38, which may be of smaller diameter than ordinarily employed but will provide ample leverage for developing the required power, which is rendered possible by 100

having the bevel-pinion 28, formed integral with the vertical shaft since by having the bevel pinion 28 integral with the shaft it may be made in the minimum diameter and yet having the proper strength. This gear wheel is provided upon its outer side with an annular set of gear teeth 39, suitably angularly arranged, in mesh with the bevel-pinion 28 and the gear wheel is provided upon its periphery with an annular set of ratchet teeth 40, for co-action with a pawl 53. The gear teeth 39 are positioned inwardly of and adjacent to the ratchet teeth 40, which extend radially outwardly beyond the diameter of the gear wheel. The ratchet teeth 40, with the co-acting pawl prevent reverse movement of the gear wheel, and these ratchet teeth being located upon the outer periphery of the gear wheel, by construction, are numerous, and positioned to reduce the leverage, or effort required for disengaging the pawl from the same, and also provide for the maximum holding adjustments of the gear wheel by the pawl. Formed integral with the gear wheel 38, and concentric therewith, is a tubular chain drum 41, rotatable upon the shaft 32'. This chain drum is positioned upon the outer side of the gear wheel 38 and, therefore, extends from the gear wheel 38 outwardly in a longitudinal direction away from the car body, the shaft 32' being, of course, horizontally arranged. This chain drum 41 is of constant diameter throughout its entire length, and is designed to produce a uniform power ratio or pull on the chain, to be described, during its operation, when a uniform power is exerted on the hand wheel. The chain drum 41 is provided with a spiral chain guiding rib 42, integral therewith, and a spiral chain bearing or supporting rib 43, also integral therewith. The spiral rib 43 extends between the turns of the spiral rib 42, while the spiral rib 42 has a much greater radial dimension, and extends radially beyond the rib 43. Both of these spiral ribs cause the chain being wound upon the chain drum 41 to progress away from the gear wheel 38 or the end of the car body, as the brakes are applied.

The numeral 44 designates a chain to be wound upon the chain drum 41, and means are provided to attach the chain to the inner end of the chain drum, adjacent to the inner ends of the spiral ribs or vanes 42 and 43. This means includes a lug 45, Figure 5, integral with the chain drum 41 and gear wheel 38, and this lug has an outer face 46, inclined with respect to the axis of rotation of the chain drum. The first end link 47 of the chain is adapted to have its side laid in contact with the inclined face 46, Figure 3, and is pivoted to the lug 45 by means of a U-bolt 48, the arms of which extend into openings 49 formed in the lug 45, one arm of the U-bolt having an opening 50, formed

therein, for the reception of a pin 51. The link 47 is pivotally held by the U-bolt 48, but upon the winding action it will lie flat upon the inclined face 46, which is adjacent to the inner end of the spiral rib 42 and equi-distantly spaced from the turns of the same, all in substantial alinement with the bearing or supporting rib 43. As a result of this arrangement and angular connection, the alternate links of the chain project into the space between the convolutions of the guiding rib 42 and become angularly positioned to contact with the winding drum 41, while their intermediate portions engage the bearing rib 43, Figure 6. The alternate links, are, therefore, turned upon their longitudinal axes and are inclined in opposite directions to bring their outer sides in contact with the periphery of the winding drum. This brings the center of the wound chain in the closest possible relation with the center of axis of rotation of the chain drum, thereby affording the maximum power or leverage. The arrangement and construction is also adapted to provide an equal bearing for all links of the chain, thereby lessening the possibility of distorting the shape of the links in the chain, when the same is being wound upon the chain drum. It might be stated at this point that when the chain is wound upon the chain drum that it is fed longitudinally and outwardly from the car body.

The chain extends downwardly for connection with the lower unit or brake applying mechanism.

In view of the foregoing description, it is thought that the invention will be fully understood.

It is to be understood that the form of my invention, herewith shown and described, is to be taken as a preferred example of the same, and that various changes in the shape, size and arrangement of parts, may be resorted to without departing from the spirit of my invention, or the scope of the subjoined claims.

Having thus described my invention, I claim:—

1. In a railway car brake, a support, a winding drum mounted thereon and said drum having a spiral supporting rib and a spiral guiding rib extending radially beyond the supporting rib, a chain attached to the drum near one end of the ribs, said chain having alternate links inclined in opposite directions to contact with the periphery of the drum between the ribs, and means to rotate the drum.

2. In a railway car brake, a support, a winding drum mounted thereon and having a uniform diameter throughout its entire effective length, said drum having a spiral supporting rib and a spiral guiding rib extending radially beyond the supporting rib, a lug secured to the winding drum near one

end thereof and having an inclined face, a chain, means for connecting the end link of the chain with the lug so that such end link may lie flat upon the inclined face, said chain having alternate links inclined in opposite directions from the supporting rib to contact with the drum between said ribs, and means to rotate the drum.

3. In a railway car brake, a support, a winding drum mounted thereon and having a uniform diameter throughout its effective length, said drum having a spiral supporting rib and a spiral guiding rib extending radially beyond the supporting rib, a lug attached to the drum near one end thereof and having an inclined face, a chain, means connecting the chain with the lug so that the end link of the chain may lie flat upon the inclined face, said chain having alternate links inclined in opposite directions from the supporting rib to contact with the drum between said ribs, a gear wheel rigidly connected with one end of the drum, and means to turn the gear wheel.

25 In testimony whereof I affix my signature.
AUGUSTUS F. KLASING.
